COMBINED BEVERAGE CART AND HOUSING FOR AN AUDIO UNIT

Claudio Palumbo, Milan, Italy, assignor to Phono-Sonic Radio Corp., Brooklyn, N.Y.

Filed Oct. 15, 1970, Ser. No. 25,516

Term of patent 14 years

Int. Cl. D6—04

U.S. Cl. D6—46

FIG. 1

FIG. 4

FIG. 1 is a perspective view of my new design for a combined beverage cart and housing for an audio unit device with the cover shown in an open position and in the remaining figures the cover is shown in a closed position;

FIG. 2 is a top plan view thereof;

FIG. 3 is a front elevational view thereof;

FIG. 4 is a side elevational view thereof; and

FIG. 5 is a rear elevational view thereof.

I claim:

The ornamental design for a combined beverage cart and housing for an audio unit, substantially as shown.
